UNITED STATES PATENT OFFICE.

DAN WIGLEY, OF BINGHAMTON, NEW YORK.

GEAR WHEEL.

Application filed October 24, 1923. Serial No. 670,497.

To all whom it may concern:

Be it known that I, DAN WIGLEY, a citizen of the United States, residing at Binghamton, State of New York, have invented 5 certain new and useful Improvements in Gear Wheels, of which the following is a specification.

This invention relates to gear construction and provides a novel gear of separate and 10 adjustable parts so combined as to permit their relative adjustment whereby a broken tooth of the gear may be replaced in a convenient and adequate manner.

Specifically, the invention provides a 15 series of laterally disposed tooth-bearing members adapted to either constitute of themselves the complete gear wheel or arranged to be mounted about the rim of the wheel body; means being provided for locking the members in place so as to permit of their relative adjustment.

Various other objects and advantages of the device may be apparent from the following description, read in connection with 25 the accompanying drawing, wherein:—

Figure 1 is a view in side elevation of the assembled wheel, the latter being shown mounted on a shaft.

Figure 2 is a vertical central section 30 through the gear body.

Figure 3 is a section along line 3—3 of Figure 4.

Figure 4 is an end elevation of the assembled gear.

Figure 5 is a transverse central vertical section of a bevel gear showing the invention applied thereto, and

Figure 6 is a sectional view showing another variation of the invention.

40 Describing the invention in detail, 10 designates a shaft upon which the gear is adapted to be mounted. In the present invention, the gear is made up of three or as many more parts as may be desired. When 45 constructed of only three parts or members the inner member 11 is provided with a plurality of keyways 12, one of which is adapted to receive part of key 13 which also engages in a suitable keyway in shaft 10.

50 Arranged on opposite sides of the central member 11 are the outer members 14 and 15, respectively. These outer members are each provided with a single keyway, as shown at 16 and 17, respectively and are 55 bolted or otherwise fastened to the central member by at least two diametrically op-

posite pins, bolts, rivets, or other fasteners 18, passing through aligned openings 19 extending transversely through the body of the gear members. In the preferred construction the two outer members are preferably provided with but a pair of such openings 19 while the central member has a circular series of such openings, as will be clearly noted from Figure 3 of the drawing. 60

Gear member 11 may be termed the adjustable member of the device in that it is adapted to be rotated about its axis for bringing one of its keyways and a pair of its openings in alignment with the proper 70 corresponding keyways and openings of the outer members 14 and 15. Each member is, moreover, provided with a suitable number of tooth portions, as shown at 20, 21, and 22, the tooth portions 21 of the central gear 75 member being centered between corresponding gear portions 20 and 22 of the outer gear members. It will thus be seen that the tooth portions of each member constitute a one-third part of each and every 80 tooth provided on the gear.

Should the gear be stripped of one or more of its teeth at any time the value of the gear will not, as is the case with present 85 type of gears, be totally lost nor its usefulness be entirely impaired. Figures 3 and 4 illustrate the manner in which the various gear members are adjusted to offset the disadvantages usually incident to the breaking or stripping of one or more gear 90 teeth. Each of the gear members are illustrated as being minus a tooth portion, as will be understood from the spaces left at 23, 24, and 25. Assuming that the tooth normally occupying the space has become 95 broken, the matter can be at once remedied by loosening fasteners 18 after removing the gear from shaft 10, and the central member 11 revolved until one of its gear portions 21 is positioned between the tooth spaces 23 100 and 25 of the outer members 14 and 15. At the same time the blank tooth space 24 of the central member comes into position between certain tooth portions 20 and 22 of the outer gear members. Consequently, instead of the tooth spaces being totally 105 blank they are now relatively positioned so as to be provided with at least one-third part of a tooth which is sufficient to insure a firm mesh with an associate gear. 110 This adjustability of the various gear plates 11, 14, and 15 enables the teeth to be re-ar-

ranged in a quick and convenient manner, thus eliminating long delay in the event of gear trouble and otherwise providing for the efficient and expeditious repairing of a 5 broken gear.

In Figure 5 is illustrated the construction of a beveled gear to which the invention is applied. In this instance the largest gear plate 26 is provided with an extended hub 10 portion 27 upon which the remaining gear plates 28 and 29 are mounted, as shown. The arrangement of the teeth of the various members are the same as explained above. Members 28 and 29 are locked about the 15 hub 27 by means of a shaft key 30 which engages in a suitable groove in the sleeve and in suitable keyways in the members 28 and 29. Member 29 is preferably provided with a plurality of keyways, each of which 20 is adapted to be brought into alignment with a single keyway in member 28, when the members are free to be relatively adjusted. The members of the beveled gear are tightened, one against the other, and 25 held firmly in place by means of a lock nut 31 which engages to secure threads on the outer end of sleeve 27. The assembled gear is locked to the shaft by means of a key or spline 32, as shown. In the modification 30 disclosed in Figure 6 the gear is constructed of a main body portion 33 which is adapted to be keyed to shaft 10 in the manner illustrated. The gear body 33 is provided along one edge with an outstanding flange 34 to which the tooth-bearing members 35, 36, and 37 are bolted by means of bolts 38. The members are further secured to the body 33 by means of one or more keys 39 engaged in suitable keyways in the body and in the 35 various members, as will be understood. It will be observed that member 35 is shouldered to engage over the flange 34 so that the teeth formed by the combined tooth portions of the associated gear members will 40 extend for the full width of the gear.

The gear wheels, as above described, can be made with any number of teeth desired of the more or less parts gearing to the purpose for which intended. The wheels can 45 also be adapted, within the scope of the in-

vention, for either square or round shafts, or any other type of shaft required.

Having thus described the invention, what I claim as new and desire to secure by Letters Patent is:—

1. A gear wheel comprising a plurality of tooth-bearing members, one of which is provided with a plurality of keyways and a series of openings concentric with the axis of the members and the remaining members being respectively provided with a single keyway and a pair of openings adapted to be brought into register with selected keyways and openings of the first mentioned member. 60

2. A gear wheel comprising three or more tooth-bearing gear members disposed side by side for relative adjustment about a common axis, said members having corresponding sets of tooth portions cooperating to form the teeth of the gear and being relatively adjustable so that a broken tooth portion of one member may be moved opposite an unimpaired tooth portion of an adjacent member whereby the broken tooth portion 70 may be partially replaced, and means for fastening the said members together in their adjusted position. 75

3. A gear wheel comprising three or more gear members mounted for adjustment 80 about a common axis, each of said gear members being provided with a corresponding number of tooth portions and all of said members being normally arranged with the tooth portions of one in alignment with 85 corresponding tooth portions of the other members, and removable means for fastening the said adjustable gear members against relative movement, said means being removable to permit one of the said 90 members to be adjusted relative to the others so that, in the event of one or more teeth being broken or stripped from the wheel, unimpaired tooth portions of one member may be positioned in alignment with the 95 impaired tooth portion of an adjacent member so as to partly replace the broken tooth.

In testimony whereof I affix my signature.

DAN WIGLEY.
